UNITED STATES PATENT OFFICE.

GEORGE T. PEARSONS, OF NEW YORK, N. Y.

FIRE-EXTINGUISHER.

1,289,253.

Specification of Letters Patent. Patented Dec. 31, 1918.

Application filed August 4, 1916. Serial No. 113,049.

To all whom it may concern:

Be it known that I, GEORGE T. PEARSONS, a citizen of the United States, residing in the borough of Manhattan, in the city, county, and State of New York, have invented new and useful Improvements in Fire-Extinguishers, of which the following is a specification.

This invention relates to fire extinguishers of the type in which a fire extinguishing liquid contained in a tank or reservoir is discharged therefrom by a pressure created within the reservoir, such as a gas pressure resulting from the reaction of the mixing of gas generating materials normally maintained in a separated condition in the reservoir. The fire extinguishing liquid used in this type of extinguisher is of such a nature that it will quickly evaporate, resulting in the necessity of frequent examination of the extinguisher and the refilling of the same, and it is an object of the present invention to provide means, which may be readily ruptured and punctured, to seal the discharge outlet of the reservoir, and to provide means operable by the pressure in the reservoir to puncture or rupture said closure to free the contents of the reservoir.

A further object of the invention relates to extinguishers of this type in which the gas is generated in a generator in the reservoir having an outlet leading into the reservoir, and the provision of means to close the outlet of the generator and to provide means, which may be readily punctured or ruptured, to close the outlet of the generator and maintain the gas generating materials in the generator free from the liquid in the reservoir, and to provide means mounted in the outlet of the generator and operable by the pressure in the generator to puncture said closure to permit of the flow of the generated gas into the reservoir.

Another object of the invention relates to improved outlet means for the reservoir and to connect said outlet to the liquid in the lowermost part of the reservoir in all positions of the latter.

In the drawing accompanying and forming a part of this specification Figure 1 is a sectional side elevation of a fire extinguisher illustrating an embodiment of my invention.

Fig. 2 is a sectional side elevation of the closures for the reservoir and generator out-

lets and the means to puncture or rupture 55 said closures, the section being taken substantially on the line 2-2 of Fig. 1 and looking in the direction of the arrows; and Fig. 3 is a section taken on the line 3-3 of Fig. 1 looking in the direction of the arrows. 60

Similar characters of reference designate like parts throughout the different views of the drawing.

In the drawing I have illustrated an embodiment of my invention in connection 65 with a fire extinguisher of the type in which the extinguisher is set in operation by inverting the extinguisher, and in which there is provided a reservoir for a fire extinguishing liquid, such as carbon tetrachlorid, said 70 reservoir preferably consisting of a cylindrical body portion 3 having an opening in one end closed by a removable cover 4, and in the normal position of the extinguisher constituting the top, the other end being closed 75 by a bottom 5 preferably dished as shown, with a rod 6 extending transversely of the dished portion to constitute a hand grip. The cover has an outlet port 7 having a discharge nozzle 8 connected thereto to extend 80 laterally of the reservoir to adjacent the side.

As stated, the fire extinguishing liquid is expelled from the reservoir by pressure created in the reservoir, such as a gas pressure generated by means in a generator in 85 the reservoir, said generator consisting of a receptacle G of a width less than the internal diameter of the reservoir and maintained centrally of the reservoir by lugs 12' on the generator engaging with the wall of 90 the reservoir to provide a space between the sides of the generator and reservoir and having a removable cover 9, said receptacle being supported and spaced from the bottom of the reservoir in the normal position of 95 the extinguisher and having an outlet tube 10 in the bottom leading into the reservoir, said tube having lateral openings, as shown, for a purpose to be hereinafter described.

A receptacle 11 having the upper end open 100 for a gas generating material, such as bicarbonate of soda, is supported in the receptacle G upon the tube 10, said receptacle being of less width than the receptacle G and maintained centrally of the latter by 105 laterally projecting lugs 12 engaging with the wall of the receptacle G. Supported in the receptacle 11 is a third receptacle 13,

such as a glass bottle, for another gas generating material, such as hydrochloric or sulfuric acid, the neck of the bottle extending to adjacent the cover 9 and having lateral openings as shown. By supporting the receptacle 11 on the tube 10 there is provided a space between the bottom of the receptacles G and 11 in which is located a material through which the generated gas 10 passes before passing out through the outlet tube 10 to filter and render the generated gas anhydrous or dry and non-acid, the said material being of a nature to absorb or neutralize any moisture or acid in 15 such gas, sodium carbonate having been found to answer the purpose.

The generator outlet is sealed to maintain the gas generating materials free from the liquid in the reservoir by means as shown in 20 Fig. 2 consisting of a fragile leaf 14, such as tin foil, secured between a pair of washers 15 and connected to the generator outlet tube by a perforated cap 16, the closure carrying washers being clamped between 25 said cap and the end of the tube 10. The closure leaf is ruptured or punctured to permit the passage of the gas from the generator into the receptacle by means operable by the pressure within the generator, and which 30 means consists of a tubular plunger (shown in a general way at 17) engaging in the tube 10 and of less diameter than said tube to provide a space between the tube and the plunger, and the plunger having a restricted outlet 18 at one end with said end of the tube pointed or beveled. The other end of the tube is slidably mounted on a perforated plug or tube 19 in the tube 10, and the perforation in the plug 19 is normally closed by 35 a plug 2^a carried by the plunger and maintained in closed position by a spring 21, this spring also retaining the plunger in position with the pointed end away from the fragile leaf closure. As gas is generated in the generator, the said gas passing through the perforated plug 19 in the outlet tube and impinging against the plug 20 will move the plunger forward and cause the pointed end 40 to pierce the fragile leaf 14. After the leaf has been punctured the gas enters between the plunger and tube 10 and passes into the plunger through lateral ports 21' and out through the restricted outlet into the reservoir. 45 To prevent evaporation of the fire extinguishing liquid in the reservoir through the discharge outlet 8, the said outlet is also sealed by a closure as shown in Fig. 2 and as used to seal the outlet of the generator, that is, a fragile leaf of tin foil carried between a pair of washers and the latter connected to the outlet tube 8 by a perforated cap 23, and the fragile leaf is also punctured by means operable by pressure from 50 within the reservoir and consisting of a

plunger the construction of which plunger and the connection thereof to the reservoir outlet being the same as the plunger 17 and the connection thereof to the generator outlet, and as shown in Fig. 2.

To connect the reservoir outlet with the liquid in the lowermost part of the reservoir in all positions of the latter there is connected to said outlet a flexible tube 25, commercially termed "flexible metallic hose", to extend into the reservoir. A rigid tube 26 extending longitudinally of the reservoir with one end adjacent the cover 4 and the other end adjacent the generator is connected between its ends to the free end 80 of the flexible tube 25.

To at all times connect the lowermost end of the tube 26 with the reservoir and shut off communication between the upper end of the tube and the reservoir there is provided a valve mechanism comprising a pair of valves 27, 28 connected by a rod 29 and adapted to coöperate with valve seats connected to or formed at the ends of the tube. To prevent said tube from engaging with the cover 4 or the generator, according to the position of the reservoir, with the consequent closing of the coöperating end of the tube, cages 30, 31 in the form of caps having lateral ports are connected to the end 95 of the tube (Fig. 3).

In operation the extinguisher is inverted causing the soda in the receptacle 11 to fall against the cover 9 of the generator and the acid in the receptacle 13 to flow through the neck perforations and mix with the soda, the resultant gas passing between the sides of the receptacles G and 11, through the filtering material into the outlet tube 10, the pressure of the gas as it enters said tube and impinges against the tubular plunger 17 forcing the restricted end of the plunger through the leaf closure and the gas then passing through said plunger into the reservoir. The generator is prevented from falling against the cover 4 by a rod 32 fixed at one end to the generator to lie adjacent the wall of the reservoir with the other end abutting against the cover 4. As the force of the gas pressure is exerted upon the liquid in the reservoir and the liquid is forced out through tube 26, tube 25 and outlet 7, and as it impinges against the plunger therein it will force the restricted end of said plunger through the leaf closure when the liquid is discharged through the outlet nozzle 8. It will be noted that the discharge tubes 25 and 26 are connected to and removable with the cover permitting of the ready removal of the generator and the thorough 110 cleaning of the extinguisher.

Having thus described my invention I claim:

1. In a fire extinguisher, the combination with a reservoir for a fire extinguishing

liquid having an outlet, of a flexible tube connected to said outlet, and a rigid tube extending longitudinally of the reservoir connected between its ends to the flexible tube, substantially as and for the purpose specified.

2. In a fire extinguisher, the combination with a reservoir for a fire extinguishing liquid having an outlet, of a flexible tube connected to said outlet; a rigid tube extending longitudinally of the reservoir connected between its ends to the flexible tube; and valves to close the opposite ends of the rigid tube, said valves being operable so that when one of the ends of the tube is closed by a valve the other end is open to the reservoir; substantially as and for the purpose specified.

3. In a fire extinguisher, the combination of a reservoir for a fire extinguishing liquid having an outlet centrally in one end; a generator in the reservoir in which to generate gas having an outlet leading into the reservoir; a flexible tube fixed at one end in the reservoir outlet and adapted to have swinging movement and a rigid tube extending longitudinally of the reservoir connected between its ends to the free end of the flexible tube to swing therewith, substantially as and for the purpose specified.

4. In a fire extinguisher, the combination of a reservoir having an opening in one end; a removable cover for said opening, said cover having an opening to constitute the discharge outlet of the reservoir; a flexible tube connected to said outlet to extend into the reservoir; and a rigid tube extending longitudinally of the reservoir connected between its ends to the flexible tube, substantially as and for the purpose specified.

5. In a fire extinguisher, the combination with a reservoir for a fire extinguishing liquid having an outlet, of a generator in which to generate gas in the reservoir having an outlet leading into the reservoir; a fragile closure connected to the generator outlet to close the same; and a tubular plunger operable from the pressures within the generator to rupture said fragile closure to

connect the generator with the reservoir, substantially as and for the purpose specified.

6. In a fire extinguisher, the combination with a reservoir for a fire extinguishing liquid having an outlet, of a generator in which to generate gas in the reservoir having an outlet leading into the reservoir; a fragile leaf closure connected to said outlet; and a tubular plunger slidably mounted in the outlet of the generator to normally be out of contact with the fragile closure, and operable from the pressures within the generator to puncture the fragile closure to connect the generator with the reservoir, substantially as and for the purpose specified.

7. In a fire extinguisher, the combination with a reservoir for a fire extinguishing liquid having an outlet, of means to create a pressure in said reservoir; a fragile closure connected to the reservoir outlet; and a tubular plunger operable from the pressures within the reservoir to puncture the fragile closure, substantially as and for the purpose specified.

8. In a fire extinguisher, the combination of a reservoir for a fire extinguishing liquid having an outlet; a generator in which to generate gas having an outlet leading into the reservoir to create pressure within the reservoir; a fragile leaf closure for the reservoir outlet; and a tubular plunger slidably mounted in the reservoir outlet and operable from the pressures within the reservoir to puncture the fragile closure, substantially as and for the purpose specified.

9. In a fire extinguisher, the combination of a reservoir for a fire extinguishing liquid having an outlet; means to connect said outlet with the liquid adjacent the side of the reservoir in all positions of the latter; means to create a pressure in said reservoir; a fragile leaf closure connected to said outlet; and a tubular plunger mounted in the reservoir outlet and operable from the pressures within the reservoir to puncture the fragile leaf, substantially as and for the purpose specified.
